The ornamental design of an automobile passenger grab handle, as shown and described.

DESCRIPTION

FIG. 1 is a front perspective view of an automobile passenger grab handle according to my new design;

FIG. 2 is a top view thereof;

FIG. 3 is a bottom view thereof;

FIG. 4 is a left side view thereof;

FIG. 5 is a right side view thereof;

FIG. 6 is a front end view thereof; and,

FIG. 7 is a rear end view thereof.

The broken lines shown in the drawings depict portions of the automobile passenger grab handle which form no part of the claimed design.
